UNITED STATES PATENT OFFICE.

JOSEPH R. BLAINE, OF OAK PARK, ILLINOIS, ASSIGNOR TO MIEHLE PRINTING PRESS & MANUFACTURING COMPANY, OF CHICAGO, ILLINOIS, A CORPORATION OF ILLINOIS.

GRIPPER MECHANISM.

Application filed October 26, 1922. Serial No. 596,939.

This invention relates to gripper mechanism.

One object of the invention is to provide an improved gripper for use on printing press cylinders, which gripper after its gripper point is seated on the fed sheet cannot move the sheet or move with respect thereto in a manner to cause the sheet to move out of register.

Another object is to provide a simple, durable and efficient gripper in which the gripper point and its operating shaft are relatively movable, additional movement of the shaft after the gripper point is seated not causing additional movement of the gripper point.

Another object is to provide an inexpensive gripper in which the associated parts cooperate in a manner to meet all of the requirements under operating conditions.

These and other objects are accomplished by means of the arrangement disclosed on the accompanying sheet of drawings, in which—

Figure 1 is a side elevation of my improved gripper mechanism, the operating shaft and a portion of the printing press cylinder being shown in section;

Figure 2 is a rear elevation of the gripper mechanism; and

Figure 3 is a sectional view taken in the plane of line 3—3 of Figure 2.

The various novel features of the invention will be apparent from the following description and drawings, and will be particularly pointed out in the appended claims.

Referring to the figures of the drawings, it will be noted that I have disclosed my invention in connection with a printing press cylinder 10 in which there is mounted an operating shaft 11 having an oscillatory movement.

The gripper proper includes a gripper point 12 and a clamp body 13. Preferably the clamp body is formed of a single piece of sheet metal and includes two side walls 14 and a top wall 15 from which extends a bracket 16 terminating in a barrel 17 for the reception of a spring 18 pressing upon the gripper point 12 for yieldably holding

the latter in position upon the cylinder pad 19 or a sheet of material placed thereon.

The clamp body is secured to the operating shaft 11 in a manner such that, when the clamp body is secured in position, there can be no relative movement between the operating shaft 11 and the clamp body 13. To this end the shaft 11 is provided with a V-shaped groove 20 into which a V-shaped key 21 fits. The key is engaged by a cone-shaped end of a clamp screw 22 which extends through the top portion 15 of the clamp member 13 and cooperates with a nut 23 whereby the clamp body is rigidly secured to the operating shaft 11.

It will be understood that the gripper point 12 and the clamp body 13 are not integrally formed but are two separate pieces. The rear portion or tail of the gripper point 70 is located between the side walls 14 of the clamp body and is formed in a loop to fit the operating shaft 11. Furthermore, the tail of the gripper point is bifurcated to form two wings 24 which are interposed between the side walls 14 and the key 21, the rear wall 25 formed by the bifurcation of the tail portion of the gripper point engaging the key in a manner to limit counterclockwise movement of the gripper point 80 12, as viewed in Figures 1 and 3, when the operating shaft 11 is moved in a manner to raise the gripper point from cylinder pad 19. In other words, the key 21 acts as a stop for the gripper point to prevent uncontrolled movement of the latter under the tension of the spring 18 when the gripper point is raised from the cylinder pad 19. From an inspection of Figures 1 and 3 of the drawings, it will be apparent that the 90 gripper pivots about the center of the operating shaft 11.

In operation, it will be understood that the operating shaft 11 rotates in a clockwise direction as shown in Figures 1 and 3 95 for raising the gripper point from the cylinder pad to permit feeding of a sheet of material under the gripper point whereupon the latter, through the counterclockwise movement of the operating shaft 11, 100 moves downwardly into engagement with the sheet of material on the pad 19. Any

continued movement of the operating shaft in a counterclockwise direction, after the gripper point is seated upon the sheet of material, is not transmitted to the gripper point; the excess movement being absorbed by the spring 18. As a result of the fact that the gripper point does not move further in the same direction after it passes into engagement with the sheet material, 10 there can be no slippage of the sheet and accordingly, the sheet cannot be moved out of register. As mentioned above, if the operating shaft 11 does oscillate an additional amount in a counterclockwise direction after the gripper engages the sheet of material, the key 21 will pass out of engagement with the stop wall 25 on the gripper point tail, and when the operating shaft 11 again moves in a clockwise direction, the 15 key 21 will pass into engagement with said stop wall 25 for preventing uncontrolled movement of the gripper point when the latter is raised from the cylinder pad 19 or the sheet material thereon.

20 25 It is my intention to cover all modifications of the invention falling within the spirit and scope of the following claims.

I claim:

1. In gripper mechanism, the combination 30 of a support, a clamp body secured to said support, and a gripper point operatively associated with said clamp body, yieldably pressed toward the latter upon a continued clamping movement of said clamp body and independently connected to said support whereby there may be no slippage of a gripped sheet after said gripper point is slated upon said sheet.
2. In gripper mechanism, the combination 40 of a support, a clamp body secured to said support, and a gripper point mounted within said clamp body and independently connected to said support whereby said clamp body and gripper point may have a relative movement during a clamping movement to prevent changing the register of a sheet after the gripper point is seated upon the sheet.
3. In gripper mechanism, the combination 50 of a support, a clamp body secured to said support, and a gripper point movably mounted on said support and within said clamp body whereby the gripper point may freely pivot about the axis of said support to prevent moving a sheet out of register after the gripper point is seated upon the sheet.
4. In gripper mechanism, the combination 60 of an actuating member, a clamp body secured thereto, a gripper point movably mounted on said member and within said clamp body, and means interposed between said clamp body and gripper point for absorbing excess clamping movement after the gripper point engages a sheet being gripped.

5. In gripper mechanism, the combination of a support, a clamp body secured to said support, a gripper point movably mounted on said support, and means associated with said clamp body and gripper point for limiting movement of said gripper point in a given direction when said clamp body is moved in a different direction.

6. In gripper mechanism, the combination of a support, a clamp body secured to said support, a gripper point movably mounted on said support and within said clamp body, and a spring interposed between said clamp body and gripper point for absorbing excess gripping movement of the clamp body 80 which otherwise would be transmitted to said gripper point.

7. In gripper mechanism, the combination of a support, a clamp body secured to said support, a gripper point movably mounted on said support, a spring interposed between said clamp body and gripper point for absorbing excess gripping movement of the clamp body which otherwise would be transmitted to said gripper point, and means associated with said clamp body and gripper point for limiting relative movement between said clamp body and gripper point in a direction in which said spring tends to move the gripper point.

8. In a gripper mechanism, the combination of a support having a V-shaped groove, a V-shaped key mounted in said groove, a clamp body mounted on said support, and a clamping screw associated with said clamp body having a cone-shaped end passing into said V-shaped key whereby the clamp body is rigidly held in position.

9. In gripper mechanism, the combination of a support having a V-shaped groove, a V-shaped key mounted in said groove, a clamp body mounted on said support, a clamping screw associated with said clamp body having a cone-shaped end passing into said V-shaped key whereby the clamp is rigidly held in position, and a gripper point movably mounted on said support having a portion engageable with said key for limiting movement of said gripper point in one direction.

10. In gripper mechanism, the combination of an actuating shaft having a V-shaped groove therein, a clamp body mounted on said shaft, a V-shaped key fitting within said groove, a screw operatively connected to said clamp body and having a cone-shaped end fitting into said key whereby said clamp body is rigidly held on said shaft, said clamp body having side walls, and a gripper point movably mounted on said shaft intermediate said clamp body side walls.

11. In gripper mechanism, the combination of an actuating shaft having a V-shaped groove therein, a clamp body mounted on

said shaft, a V-shaped key fitting within said groove, a screw operatively connected to said clamp body and having a cone-shaped end fitting into said key whereby said clamp body is rigidly held on said shaft, said clamp body having side walls, a gripper point movably mounted on said shaft intermediate said clamp body side walls, and a

spring interposed between said clamp body and said gripper point for absorbing excess movement from said shaft to said gripper point.

Signed at Chicago, Illinois, this 23rd day of October, 1922.

JOSEPH R. BLAINE.
